GARMENT HANGER

Samuel Zirin, Brooklyn, N. Y.

Application August 21, 1943, Serial No. 499,528

5 Claims. (Cl. 223—94)

This invention relates to a garment hanger.

Ladies' dresses generally have some closure means at the neck. At the factories where these dresses are manufactured, these closures are secured during the final pressing operation, and a hanger is inserted to support each dress until it is to be shipped.

The usual hanger consists of a bar of wood through which extends a bent piece of metal to provide a support to be hooked over the bar of a rack. When the dresses are to be packed, the packer must remove the hanger from the dress. Usually, when the packer is separating the dress from the hanger, he must slip the hanger down into the sleeve of the dress in order to manipulate it into a position where he can pull it out through the neck. This consumes time, and may result in distortion of the pressed dress.

It is an object of the invention to provide a hanger from which a dress may, by a simple manipulation, be released without requiring movement of the hanger into the sleeve of the dress, and without distorting the dress from its finally pressed appearance.

The hanger may be made in a pair of sections, connected together so that they may move apart merely under the action of the weight of the dress. Thus, when the packer manipulates a release, positioned so that such manipulation involves no distortion of the dress fabric, since such release is actuated substantially at that part of the hanger which is exposed when the dress is hanging on the hanger, the hanger will break to permit its withdrawal through the neck.

A further object of the invention proposes forming the bent piece of metal which forms the hook of the hanger of separate sections pivotally connected together in a manner to permit the top portion of the hook to assume an inoperative pivoted position extended substantially along the supporting rod of the hanger.

Another object of the invention proposes the provision of a means for locking the sections of the hook in an aligned upwardly extending position in a manner to rigidly connect the sections and permit the top portion of the hook to be engaged over the horizontal bar of a clothes rack.

It is a further object of this invention to provide a single operating means for controlling the breaking of the hanger rod and the pivoting of the hook sections in a manner to permit the rod to be broke and the top end of the hook to be bent into an inoperative position to reduce the overall size of the hanger to facilitate its being packed into a small space.

Other objects of this invention will be set forth hereinafter, or will be apparent from the description and the drawings in which is illustrated an embodiment of apparatus for carrying out the invention.

The invention, however, is not intended to be restricted to any particular construction, or to any particular arrangement of parts, or to any particular application of any such construction or any such arrangement of parts, or to any specific method of operation, or to any of the various details thereof, even where specifically shown and described herein, as the name may be modified in various particulars, or may be applied in many varied relations, without departing from the spirit and scope of the claimed invention, a practical construction embodying certain details of the invention being illustrated and described, but only for the purpose of complying with the requirements of the Statutes for disclosure of an operative embodiment, but without attempting to disclose all of the various forms and modifications in which the invention might be embodied.

On the drawings, in which the same reference characters refer to the same parts throughout, and in which is disclosed such practical construction:

Fig. 1 is an elevational view of a garment hanger embodying the features of this invention, a garment being shown schematically arranged on the hanger by the dot and dash lines.

Fig. 2 is a fragmentary enlarged longitudinal sectional view of a portion of Fig. 1.

Fig. 3 is a transverse sectional view taken on the line 3—3 of Fig. 2.

Fig. 4 is a fragmentary bottom view looking in the direction of the line 4—4 of Fig. 2.

Fig. 5 is a fragmentary elevational view of a garment hanger constructed according to another form of this invention.

Fig. 6 is a fragmentary bottom view looking in the direction of the line 6—6 of Fig. 5.

Fig. 7 is an elevational view of a garment hanger, embodying further features of the invention, a garment being shown arranged on the hanger, the garment being shown by dot and dash lines.

Fig. 8 is an elevational view similar to Fig. 7 but with the portions of the garment hanger pivoted to their inoperative positions.

Fig. 9 is an enlarged detailed vertical sectional view of a portion of Fig. 7.

Fig. 10 is a practical horizontal sectional view on the line 10—10 of Fig. 9.

Fig. 11 is a sectional view substantially on the line 11—11 of Fig. 9.

Fig. 12 is a vertical sectional view similar to Fig. 9 but with the parts of the hanger substantially in the position shown in Fig. 8.

The garment hanger 11, in accordance with the form of the invention illustrated in Figs. 1-4 inclusive, has a supporting rod 13 intended to be disposed substantially horizontal of a dress 14 which is supported by the hanger. Extending vertically upwards from the supporting rod 13 is a hanger support 15 which terminates in a hook 17 which may be slipped over a bar or pole.

The rod 13 may be of any suitable material, as for example, wood. In the particular form of the invention shown, the rod 13 is made up to include a bar 19 and a supporting section 21. The bar 19 and section 21 may be positioned in relation to each other so that they together form substantially the usual supporting rod 13 of the clothes hanger. However, the bar 19 and supporting section 21 are entirely distinct and separate members. The respective end edges 23 and 25 of the said bar 19 and supporting section 21 are intended to be brought into juxtaposition to form the substantially single supporting rod 13.

Positioned on the end edge 23 is a metal section 27. Section 27 is secured on said end edge portion 23 in a suitable manner, as for example, by the prongs 29 stamped from the material of the section 27. Secured to the end edge portion 25 is a metal section 31 which is secured to the supporting section 21 in a like manner, by means of prongs 29 stamped from the metal of the section 31. The sections 27 and 31 have inter-engaged coil portions 33 and 35, respectively, through which a pintle rivet 37 passes to hingedly connect these parts. A spring finger 39 is located within the section 31 and is fixedly held upon a wall thereof by a rivet 41. This spring finger 39 has a laterally extending portion 43 which is formed with an upwardly stamped prong 45 engageable with a downwardly stamped keeper 47 from the section 27. The finger 39 is also provided with a depressible button 49 which projects from an opening 51 formed in the section 31. The hanger support 15 passes through the materials of the sections 21 and 31, and at its bottom end is formed with a riveted head 53 which turnably supports the hanger support 15 in position.

As illustrated in Figs. 1-3 the hanger is in condition to be used to support a dress or garment 14. When desired the button 51 may be depressed to flex the spring finger 39 downwards so that the prong 45 disengages from the keeper 47. This frees the section 27 and then the bar 19 and section 21 may be folded downwards and the folded hanger slipped upwards out of the neck of the dress 14 or other garment. When the bar 19 and section 21 is moved back to their initial positions the prong 45 will re-engage the keeper 47 to hold the bar 19 and section 21 in aligned positions.

In Figs. 5 and 6 a modified form of the invention has been disclosed which distinguishes from the prior form in the construction of the hanger support 15. This hanger support has a bifurcated bottom end 15a, the fingers of which are pivotally engaged beneath the heads and around the pintle rivet 37. The bifurcated bottom end 15a is produced by having a finger section 15x mounted upon the bottom portion of the hanger support 15. In other respects this form of the invention is identical to the previous form and

like parts are indicated by like reference numerals.

The garment hanger 10, shown in Figs. 7 to 12 of the drawings, has a supporting rod 12, intended to be disposed substantially horizontally when a dress 14 is assembled on the rod. Extending vertically upwardly from rod 12 is a hanger support 16, which terminates in a hook 18, which may be slipped over a bar or pole.

10 Rod 12 may be of any suitable material, as, for instance, wood. In the particular instance shown, rod 12 is made up to include a bar 20 and a supporting section 22. As shown in Fig. 7, bar 20 and section 22 may be positioned in relation to each other so that they together form substantially the usual supporting rod 12 of a clothes hanger. However, bar 20 and supporting section 22 are entirely distinct members. Respective end edges 24 and 26 of bar 20 and supporting section 22 are intended to be brought into juxtaposition to form the substantially single supporting rod 12.

Positioned on end edge 24 is a metal section 32. Section 32 is secured on end edge 24 in a suitable manner, as for instance, by prongs 34 stamped from the section 32. Secured on end edge 26 is a metal section 36 which is secured to the supporting section 22 in like manner by like means. Sections 32 and 36, respectively, have ears 38 and 40 substantially of the same contour and intended to be overlapped as shown in Fig. 11. A cylindrical washer 42 is disposed between ears 38 and 40 and upon a rivet 44 to retain the ears spaced apart, rivet 44 providing a pivot for ears 38 and 40. Thus bar 20 and supporting section 22 are retained assembled as on a hinge. It can easily be understood that washer 42 might be integral with either edge 24 or edge 26 if desired.

40 A spring finger 50 is located within section 36 and extends beyond front edge 52 of section 36 and presents a prong 54 extending upwardly from finger 50. The prong 54 is formed by being pushed directly out of the metal of finger 50 or if desired may be of a separate piece of metal secured to the top face of the finger 50 in any desired manner. A button 66 has a portion fitting loosely through a longitudinally extended elongated opening 68 in section 36, forming a projecting end for the manipulation of the finger 50.

45 A portion of metal section 32 is stamped out to provide a keeper 78 for engagement by prong 54 when bar 20 and supporting section 22 are swung around the pivot of rivet 44 to form the substantially continuous supporting rod 12, as shown in Fig. 8.

50 The hanger support 16 is constructed of separate sections consisting of a base section 80 and a head section 82. The base section 80 is constructed of a length of wire or rod material and is extended upwards through an opening in the supporting section 22 and through an elongated longitudinally extending opening 84 formed in the tail end of the finger 50. The free top end of the base section 80 is then extended outwards through an opening formed in the top wall of the metal section 36. The bottom end of the base section is milled over at 86 to prevent upward movement of the base section 80 relative to the supporting section 22. Likewise, a portion of the base section 80 within the supporting section 22 is wedged at 88 to prevent rotation of the base section 80 relative to the supporting section 22.

55 A sleeve 90 is mounted upon the top portion of the base section 80 and pivotally supports the head section 82 which continues into the hook 18. A pin 92 is extended through the base sec-

tion 80 and has its ends projected beyond the sides of the base section to engage vertical elongated slots 94 formed in the sides of the sleeve 90. This engagement of pin and slots holds the sleeve against rotating relative to the base section 80 but permits the sleeve to slide vertically thereto. The top end of the sleeve 90 is projected through the opening 84 formed in the tail end of the finger 50 and out through the opening formed in the top wall of the metal section 36.

Means is provided for locking the sleeve 90 in a position in which the ends of the pins 92 will be disposed within the top portion of the slots 94. This means comprises pins 96 which extend laterally from the sides of the sleeve 90 and which engage the bottom face of the tail end of the finger 50. The finger is formed with cutouts 98 which extend laterally from the sides of the opening 84. Normally, the pins 96 and the cutouts 98 are out of alignment as shown in Figs. 9 and 10 to retain the sleeve 90 in its lowered position. In the disengaged position of the prong 54 from the keeper 78 it is possible to slide the finger 50 relative to the sleeve 90 to align the pins 96 and the cutout 98 to permit the pins 96 to move upwards through the cutouts 98 when the sleeve 90 is pulled vertically upwards.

The head section 82 of the hanger support 16 is formed of tubular material and is formed at its bottom end with a pair of downwardly extending fingers 100 which overlap the top end of the sleeve 90. These fingers 100 are pivotally attached to the top end of the sleeve 90 by means of pins 102. The relation between the head section 82, the base section and the sleeve 90 is such that when the sleeve 90 is in its lowered position the top end of the base section 80 will be extended into the bottom end of the head section 82 and maintain the head section in an operative position extended vertically upwards from the base section 80 as shown in Figs. 7 and 9. On the other hand, when the sleeve 90 is moved to its raised position on the base section 80 (see full lines on Fig. 12) the head section 82 will also be moved vertically causing the top end of the base section 80 to be withdrawn from the bottom end of the head section 82 permitting the head section to be pivoted to its inoperative position along the supporting section 22 as shown by the dot and dash lines in Fig. 12 and the full lines in Fig. 8.

Resilient means is provided for shooting the sleeve 90 into its vertically raised position to free the head section 82 the moment the finger 50 is moved longitudinally of the supporting section to align the pins 96 and the cutouts 98. This means comprises an expansion spring 104 disposed within the bottom portion of the head section 82. The top end of the spring 104 is securely mounted upon a peg 106 extended diametrically across a portion of the head section 82. The bottom end of the spring 104 engages the top end of the base section 80 under pressure to urge the sleeve 90 upwards when the pins 96 and cutouts 98 are aligned.

Now, with a garment or dress 14 supported on the extended rod 12 of Fig. 7, the packer, holding the hanger and the garment by grasping hook 18 with one hand, can, with his free hand, release bar 20 by bearing against button 66 which will be located at the opening of the neck of the garment. The weight of the garment on bar 20, now that prong 54 is disengaged from keeper 78, will cause bar 20 to fall downwardly. Then the entire hanger may be removed through the neck of the

garment without further manipulation. Thus the dress, without opening the closed neck, and without shifting the hanger into the sleeve of the garment, may be packed.

- 5 To move the parts of the hanger 10 from the position shown in Fig. 7 to the position shown in Fig. 8 the button 66 is pressed inwards disengaging the prong 54 from the keeper 78 permitting the bar 20 to pivot about the rivet 44.
- 10 In the disengaged position of the prong 54 and the keeper 78 the finger 50 is moved longitudinally of the supporting section 20 by pushing on the bottom 66. This will cause the pins 96 and cutouts 98 to be aligned freeing the sleeve 90.
- 15 Immediately, the spring 104 will urge the head section 82 and sleeve 90 upwards as a unit relative to the base section 80. This upward movement will disengage the top end of the base section from the bottom end of the head section 82 causing the head section 82 to assume the position illustrated by full lines in Fig. 12. In this position the head section 82 is free and may be moved to the position illustrated in dot and dash lines in Fig. 12. To restore the hanger 10 to the position shown in Fig. 7, the above procedure is reversed.

It is to be understood that instead of the upwardly projecting keeper 78 any other suitable projecting abutment may be formed by denting a portion of section 32 which is to be engaged by the prong 54 of the finger 50. The dent in the section 32 may also be pressed downwardly, if so desired, and the shape of the engaging tongue may be formed to engage this downwardly extended dent.

Many other changes could be effected in the particular apparatus designed, and in the method of operation set forth, and in specific details thereof, without substantially departing from the invention defined in the claims, the specific description being merely of an operative embodiment capable of illustrating certain principles of the invention.

Having thus described my invention, what I claim as new, and desire to secure by United States Letters Patent is:

1. A garment hanger, comprising a transverse supporting bar, a transverse supporting section, the bar and the section having end faces formed for abutment with each other, a hinge connection at the end faces to permit the bar to move downwardly relative to the supporting section, a hanger support mounted on said supporting section and having a base section and a head section pivotally mounted on the base section, a latch spring finger internally slidably mounted on said supporting section, an internal latch prong on said bar cooperative with said latch finger for locking said bar and supporting section so that the end edges are substantially in abutment for defining substantially a single continuous garment carrier, and means for releasably holding said head section in a fixed upward directed position and including an operator pin releasably held by said latch finger.
- 50 2. A garment hanger, comprising a transverse supporting bar, a transverse supporting section, the bar and the section having end faces formed for abutment with each other, a hinge connection at the end faces to permit the bar to move downwardly relative to the supporting section, a hanger support mounted on said supporting section and having a base section and a head section

- 55 60 65 70 75 pivotally mounted on the base section, a latch

spring finger slidably mounted on said supporting section, a latch prong on said bar cooperative with said latch finger for locking said bar and supporting section so that the end edges are substantially in abutment for defining substantially a single continuous garment carrier, and means for releasably holding said head section in a fixed upward directed position and including an operator pin releasably held by said latch finger, said base section being formed with a sleeve arranged to slide vertically of said base section and said head section being pivotally mounted on the top end of said sleeve.

3. A garment hanger, comprising a transverse supporting bar, a transverse supporting section, the bar and the section having end faces formed for abutment with each other, a hinge connection at the end faces to permit the bar to move downwardly relative to the supporting section, a hanger support mounted on said supporting section and having a base section and a head section pivotally mounted on the base section, a latch spring finger slidably mounted on said supporting section, a latch prong on said bar co-operative with said latch finger for locking said bar and supporting section so that the end edges are substantially in abutment for defining substantially a single continuous garment carrier, and means for releasably holding said head section in a fixed upward directed position and including an operator pin releasably held by said latch finger, said base section being formed with a sleeve arranged to slide vertically of said base section and said head section being pivotally mounted on the top end of said sleeve, said operator pin being mounted on said sleeve and engageable beneath a portion of said latch spring finger for holding said sleeve in a downward position in which the top end of said base section will be projected into the bottom end of said head section for locking said head section in an operative position extended vertically upwards of said base section.

4. A garment hanger, comprising a transverse supporting bar, a transverse supporting section, the bar and the section having end faces formed for abutment with each other, a hinge connection at the end faces to permit the bar to move downwardly relative to the supporting section, a hanger support mounted on said supporting section and having a base section and a head section pivotally mounted on the base section, a latch spring finger slidably mounted on said supporting section, a latch prong on said bar cooperative with said latch finger for locking said bar and supporting section so that the end edges are substantially in abutment for defining substantially a single continuous garment carrier, and means for releasably holding said head sec-

tion in a fixed upward directed position and including an operator pin releasably held by said latch finger, said base section being formed with a sleeve arranged to slide vertically of said base section and said head section being pivotally mounted on the top end of said sleeve, said operator pin being mounted on said sleeve and engageable beneath a portion of said latch spring finger for holding said sleeve in a downward position in which the top end of said base section will be projected into the bottom end of said head section for locking said head section in an operative position extended vertically upwards of said base section, said latch spring finger being formed with a cutout alignable with said operator pin in the unlocked position of said finger for freeing said sleeve to move upwards relative to said base section and correspondingly move to said head section to free the same.

5. A garment hanger, comprising a transverse supporting bar, a transverse supporting section, the bar and the section having end faces formed for abutment with each other, a hinge connection at the end faces to permit the bar to move downwardly relative to the supporting section, a hanger support mounted on said supporting section and having a base section and a head section pivotally mounted on the base section, a latch spring finger slidably mounted on said supporting section, a latch prong on said bar cooperative with said latch finger for locking said bar and supporting section so that the end edges are substantially in abutment for defining substantially a single continuous garment carrier, and means for releasably holding said head section in a fixed upward directed position and including an operator pin releasably held by said latch finger, said base section being formed with a sleeve arranged to slide vertically of said base section and said head section being pivotally mounted on the top end of said sleeve, said operator pin being mounted on said sleeve and engageable beneath a portion of said latch spring finger for holding said sleeve in a downward position in which the top end of said base section will be projected into the bottom end of said head section for locking said head section in an operative position extended vertically upwards of said base section, said latch spring finger being formed with a cutout alignable with said operator pin in the unlocked position of said finger for freeing said sleeve to move upwards relative to said base section and correspondingly move said head section to free the same, and resilient means for shooting said head section and sleeve upwards as a unit in the aligned position of said operator pin and cutout.

SAMUEL ZIRIN
